DESIGN FOR A CARPET SWEEPER SHELL

Irving Richardson, Newark, N. J.

Application January 11, 1939, Serial No. 82,279

Term of patent 7 years

To all whom it may concern:

Be it known that I, Irving Richardson, a citizen of the United States, residing in the city of Newark, county of Essex, and State of New Jersey, have invented a new, original, and ornamental Design for a Carpet Sweeper Shell, of which the following is a specification, reference being had to the accompanying drawing, forming part thereof.

Fig. 1 is a top plan view of a carpet sweeper shell showing my new design;

Fig. 2 is an end elevational view thereof; and Fig. 3 is a front elevational view thereof.

The design consists of curved corners continued at the opposite sides of the carpet sweeper shell as continuous, smoothly blending curved lines, as clearly shown in Fig. 1.

I claim:

The ornamental design for a carpet sweeper shell, as shown and described.

IRVING RICHARDSON.
